UNITED STATES PATENT OFFICE.

FRED A. DOLPH, OF WASHINGTON, DISTRICT OF COLUMBIA.

PRINTING AND CASTING MECHANISM.

Application filed June 27, 1924. Serial No. 722,779.

This invention relates to a combination printing and casting machine, the printing mechanism being of the type disclosed in my Patent No. 1,232,246, dated July 3, 1917, and 5 in my co-pending application, Serial No. 696,890, filed March 4, 1924 now Patent No. 1,542,222.

In my patent and co-pending application referred to above I have disclosed a type-10 writing machine or "rapid type printer" wherein the letter keys may be simultaneously depressed in word or other suitable combinations, and one wherein it is unnecessary to actuate a space-bar to provide for 15 proper spacing. The machine comprises a plurality of movably mounted type bars, the letters of the entire alphabet being formed on the upper face of each bar. Means are provided for moving the type bars into engagement with the depressed letter keys, thereby bringing into alignment the letter characters it is desired to print. Mechanism is also provided for moving a paper carrying platen into printing engagement 20 with the aligned characters, an entire line being printed in one operation. The parts 25 are automatically returned to normal position.

One of the objects of the present invention 30 is to provide, in combination with a rapid type printer of the above type, casting mechanism for casting a linotype or a multigraph slug at the time the aligned characters are printed, the cast slug having letter characters thereon corresponding to the printed line.

The linotype or casting machines in common use today, for newspaper and other similar work are provided with a key-board 40 and casting mechanism whereby the operator is enabled to cast, from molten metal, a solid slug or linotype bearing on its upper surface characters corresponding to the keys actuated. In order to check the accuracy of 45 the work of the operator, it is necessary to assemble the cast slugs in a proofing apparatus and take a proof of the linotype slugs. With my combination printing and casting machine, the operator simultaneously prints 50 the characters and casts the linotype slug, thus obtaining a proof of the cast characters or type without the necessity of setting up the linotype slugs or blanks in a proofing apparatus. Both of these operations may 55 be performed in less time and with less effort

than is required to actuate the ordinary typewriter.

Other objects of the present invention are to provide novel type bars, for my combination machine, having raised characters 60 formed on the upper surface thereof for use in the printing operation, and having in their lower surface recessed or indented characters corresponding to, and in register with, those on the upper surface; to provide 65 an improved valve mechanism for controlling the flow of molten metal from a heated reservoir into the mold; to provide means for positively ejecting a cast slug from the mold; to provide means common to the 70 printing and casting mechanisms for actuating the same; and to provide means for disconnecting the casting mechanism in order that the machine may be employed solely as a rapid type printer when desired. The 75 above and other objects will appear more fully hereafter.

In order that the invention may be clearly understood reference is had to the accompanying drawings, wherein

Fig. 1 is a side elevation partly in section, 80 of my improved combination machine;

Fig. 2 is an enlarged sectional detail view 85 with parts broken away, of the valve mechanism and delivery chute;

Fig. 3 is an enlarged detail sectional view 85 illustrating the mold mechanism;

Fig. 4 is a detail partly in section of the mechanism for actuating the valve;

Fig. 5 is a detail plan view of one type 90 of means, that may be employed for disconnecting the linotype or casting mechanism;

Figs. 6 and 7 are side elevation and end views, respectively, of the linotype slug or blank;

Fig. 8 is a top plan view of a portion of 95 one of the type bars;

Fig. 9 is a section taken on the line 9—9 of Fig. 8;

Fig. 10 is a side elevation of one type of 100 mold that may be employed;

Fig. 11 is a top plan view, partly in section, of a mold that may be employed for casting multigraph slugs;

Fig. 12 is an enlarged sectional detail view 105 of the multigraph mold mechanism;

Fig. 13 is a sectional detail illustrating a multigraph slug ejected from the mold; and,

Fig. 14 is a front elevation of a part of 110 ejector bar.

Referring to the drawings wherein like reference numerals refer to like parts throughout the several views, and particularly to Fig. 1, the elements of the machine are preferably supported on a triangular-shaped frame having a base 1, a rear upright portion 2, and an inclined front portion on which is mounted a bed-plate 3. Slidably carried on the upper surface of plate 3 is a carriage frame which is constituted by two side members 4, 4 and two transverse end portions 5 and 5'. A type carriage 6, which is formed as a flat tray, rests on plate 3 within the three sides of the carriage frame, and is normally in engagement at its lower end with the lower transverse member 5 of the carriage frame. A transverse opening 7 is provided in the bottom of carriage 6 for a purpose to be described hereafter.

Slidably mounted on the upper surface of carriage 6 are a plurality of type bars 9, each bar having formed on the upper surface thereof capital and small letters of the entire alphabet, punctuation marks, numerals, etc., and in the lower surface thereof, corresponding aligned or registering characters 10 (see Figs. 8 and 9). Any desired number of these bars may be provided, but I have found that fifty-five will meet all ordinary requirements. Secured to the lower end of each type bar, or formed integrally therewith, are selector arms 11 which extend upwardly, at right angles to the bars, and outwardly in a manner that is illustrated and described in my Patent No. 1,232,246. Normally, the lower edges of arms 11 are in engagement with carriage 6, as illustrated in Fig. 1. To insure movement of the type bars with carriage 6 and the carriage frame, there are preferably provided a plurality of spring clips 12 positioned in slots, and brazed therein if desired, in the upper and lower carriage frame portions 5 and 5', which clips are normally in gripping engagement with the lower ends of selectors 11. Spring clips 12 also insure movement of carriage 6 with said carriage frame due to their engagement with said selector arms.

Mounted above the lower end of bed-plate 3 and at a sufficient height above base 1 to insure easy operation, is a key-board frame comprising upper and lower perforated key-supporting boards 13 and 14 which are rigidly attached in any suitable manner to an outer frame 15. Extending transversely of the machine and positioned at equal intervals between upper and lower supports 13 and 14, are a plurality of leaf springs 16, having engagement, preferably, with the upper face of letter keys 17. The latter may be formed of thin metal strips approximately 1-3/4 inches long and 1/4 inch wide, bent into a curve at the top, and suitably lettered, keys being provided for each letter of the

alphabet and as many additional keys being provided as may be necessary for punctuation marks such as the comma, interrogation mark, etc. Keys 17 are slidably positioned in registered perforations or slots 70 formed in upper and lower supports 13, 14 and are normally resiliently held in raised position by the leaf springs, as illustrated in Fig. 1. A vertical row of keys 17 is provided for each type bar and when 55 type bars are employed, 55 vertical rows of keys will be employed, as shown in my co-pending application above referred to.

Means of any suitable type are provided for selectively controlling the distance the keys 17 may be depressed and for returning the depressed keys to "capital letter" or normal, raised position. Such means are fully disclosed in my patent and co-pending application, and form no part of the present invention, it being only necessary to point out that the keys may be returned to raised position, from depressed position, by actuation of lever 18 which forces a shift bar 19 upwardly and thereby returns the depressed key or keys to their normal raised position. Any suitable type of platen 20, and platen actuating mechanism, may be employed for carrying the paper which is forced through opening 21 formed in inking plate 22, into contact with the aligned characters to be printed. The mechanism illustrated forms no part of the present invention and is fully described in my co-pending application referred to.

My rapid printing and linotype machine may be actuated by power means if desired, but preferably the printing operation is manually performed. To this end there are provided on either side of the main frame, stub shafts 23 on which are rotatably mounted sectors 24 which carry at the upper ends of their peripheries, an operating rod 25 extending transversely of the machine. While only one side of the machine is illustrated it will be understood that, unless otherwise stated, the various parts are duplicated on the opposite side. The platen mechanism is connected to rod 25 by means of link 26 and crank 27. Secured to the periphery of sector 24 is a flexible band 28 extending rearwardly over a pulley 29 that is rotatably mounted on a sub-shaft 30 secured to the side of the main frame. The lower end of flexible band 28 is secured to the periphery of a wheel 31 rigidly mounted on a transversely extending shaft 32. Formed integrally with wheel 31, if desired, is a drum 33 having secured to the periphery thereof a flexible member 34 which extends upwardly over a pulley 35 rotatably mounted adjacent the top of the main frame. A weight 36 is attached to the free end of flexible member 34 for a purpose to be explained hereinafter. Secured to member 34, adjacent pulley 35, is

5 a roller supporting bracket 37 provided with upwardly extending arms 38 for carrying a plurality of inking rollers 39 which normally rest on the surface of ink plate 22 provided with the opening 21, in the center of which opening the type characters to be printed are aligned. As illustrated in Fig. 1, the upper ends of side members 4 of the carriage frame are secured as at 8 to roller bracket 37.

10 Any suitable type of casting mechanism may be employed for forming a suitable slug or blank of the printed line. I consider it desirable, however, to provide common actuating means for the printing and casting mechanisms, and the two operations are preferably performed simultaneously. To this end there are loosely mounted on shaft 32 a pair of drums or wheels 40 (see Figs. 1 and 20 4) provided with grooves 41 in the inner faces thereof, said grooves being circular at their inner portions and helical at their outer portions. Extending into each groove, one at each side of the machine, is a pin 42 carried on the lower arm 43 of a bell crank lever that is pivotally secured to bed plate 3 as at 44. The upper arm 45 of said lever has attached to its extremity a transversely 25 extending mould 46 that is slidably mounted in a mould casing 47 which is secured in any suitable manner to the main frame of the machine below bed plate 3. Mold 46, which is adapted for forming a linotype slug, is provided with an ejector plate 48, which, 30 when the mold is in raised or molding position, is withdrawn into a recess 49 in said mold, the movement of the ejector being controlled by a pin 50, carried by an arm 51 secured to ejector plate 48, that extends into 35 a curved slot 52 formed in the inner end wall of the mold casing 47.

40 Pivots secured to the lower surface of bed plate 3, as at 53, are a pair of levers 54 provided at their lower ends with pins or 45 rollers 55 that have engagement with cam surfaces 56 formed on the outer edges of the peripheries of wheels 40. The upper ends of levers 54 are pivotally connected at 57 to the opposite ends of a valve 58 which controls 50 the flow of molten metal into mold 46. A plurality of circular openings 59 are provided in valve 58, and these openings are normally closed by a plurality of spaced lugs 60 which are formed integral with or secured to mold casing 47.

55 A reservoir 61 is positioned at a suitable distance above valve 58 for receiving the metal to be used in the casting operation. This receptacle is heated by a suitable burner 62 and is in communication with the valve mechanism via a downwardly extending duct 63. Reservoir 61, burner 62 and duct 63 may be insulated from the adjacent mechanism by asbestos or any other suitable 60 non-conductor of heat if desired. A receiv-

ing tray 64 may be provided below mold casing 47 for receiving the cast slugs.

Means are preferably provided for disconnecting the casting mechanism, whereby the machine may be operated solely as a rapid type printer. The disconnecting mechanism as disclosed comprises a pair of keys 65 slidably mounted in a groove 66 formed in shaft 32, and adapted to be moved into corresponding grooves or keyways formed in 75 the hubs of wheels 40. Projecting from the inner adjacent ends of keys 65 are pins 67 that extend into arcuate slots 68 formed in a rotatable disk 69 that may be locked in adjusted position by means of set screw 70. 80

Operation. The parts being in their normal position as illustrated in Fig. 1, and it is desired to cast a linotype slug and print, for example, the line "This line is printed in silence with but ten strokes" the letter keys 85 for the word "This" are simultaneously depressed in the four left hand vertical columns of keys 17. The next vertical column of keys is skipped and the keys for the word "line" are depressed simultaneously or singly, as desired, in the next adjacent vertical columns, etc. The letter keys for the line thus being depressed or set, the operator now moves rod 25 downwardly whereby movement is transmitted through bands 28 90 and 34 to the carriage frame through members 4, 4, platen link 26, and inking rollers 39. The engagement of spring clips 12 with the selector arms 11 cause type bars 9 and carriage 6 to be moved downwardly along 95 the bed-plate 3. As the selector arms engage the depressed letter keys 17 the desired characters on the upper and lower surfaces of the type bars are brought into alignment directly underneath the opening 21 in ink- 100 plate 22. Immediately thereafter inking rollers 39 pass over the aligned characters on top of the bars and continue on to the lower portion of the ink-plate. A lug 71 which projects from the side of the main frame, 105 in the path of carriage 6, prevents further downward movement of said carriage while the carriage frame continues its movement until it encounters the inner face 15' of the end of the keyboard frame. The movement 110 of carriage 6 is arrested at such a point as to bring opening 7 into register with the opening in the upper end of mold casing 47.

115 Simultaneously with the movements above stated the paper carrying platen 20 is moved downwardly into engagement with the aligned characters and the line is printed. The rotation imparted to shaft 32, by means of the flexible members 28, rotates drums 40 thereby forcing the upper arm 45 of the bell 120 crank levers upwardly and causing mold 46 to pass through opening 7 in the carriage 6 and into register with valve 58. Rotations of drums 40, due to the cam surfaces 56, swing levers 54 about their pivots 53 to move 125 130

control valve 58 to open position, i. e., openings 59 are brought into register with the openings between lugs 60. Molten metal in reservoir 61 passes through openings 59 into the mold and flows upwardly into the recessed characters in the bottom of type bars 9. Escape of the molten metal past the bottom of the mold is prevented by means of the lip 46' of mold 46 which abuts against the lower ends of lugs 60. The use of lug 71 to limit the movement of carriage 6, and the circular form of the inner portion of grooves 41, results in mold 46 being held in casting position over an interval long enough to ensure a good casting.

When the operator releases rod 25 weight 36 returns the parts to their normal positions. As the mold 46 moves downwardly to the bottom of the mold casing 47, pin 50, moving in groove 52, forces ejector 48 upwardly and rearwardly and the cast slug is forced into the opening 47' formed on the inner surface of the upper roll of the mold casing, the shoulders 46'' (Fig. 10) formed on mold 46, having positively forced the slug downwardly. As mold 46 again moves upwardly the previously cast slug falls into the tray 64. It will be understood that as weight 36 returns the parts to their normal positions the first operation results in valve 58 being closed to prevent any further flow of molten metal from reservoir 61.

If it is desired to operate the machine as a rapid type printer only, the casting mechanism may be disconnected by loosening set screw 70 and rotating disk 69, whereupon keys 65 are withdrawn from engagement with drums 40 and any further rotation imparted to shaft 32 is ineffective for rotating said drums and, consequently, for opening the control valve 58.

Several hours are required at present to set a single page of multigraph material and, so far as I am aware, no means have heretofore been provided for overcoming this difficulty. By the use of a suitable mold, which may be so constructed as to be interchangeable with the molding mechanism described above, a page of multigraph material may be set with my improved machine in not over ten minutes, and a proof of the same is obtained while the slugs are being cast. Referring to Figs. 11 to 14 inclusive, 72 is one type of mold which may be satisfactorily employed for casting a multigraph slug 73. Mold 72, which is provided with a longitudinal shoulder 72', is removably secured as by means of screw 74 to the ends of upper arms 45 of the bell crank levers heretofore described. A mold casing 75, which may be formed integrally, if desired, with the casing 76 of a heater or burner 77, is provided at its opposite sides with curved grooves 78 into which extend pins 79 that are formed on the ends of an ejector beam 80. Rigidly secured

adjacent each end of beam 80 is a supporting member 81 that is rigidly attached at its upper end to a transversely extending bar 82 provided on its lower edge with a plurality of evenly spaced shoulders 83. Spaced at equal intervals intermediate the end of beam 80 are a plurality of ejector rods 84 which extend into openings 85 formed in the rear wall of mold 72. Positioned at the lower end of the spout 63 of reservoir 61 is a transversely extending member 86 which is provided with a plurality of circular openings that are equally spaced at intervals corresponding to the spacing of the openings 59 in the valves 58 which has been described above.

When the operator moves the rod 25 downwardly, motion is transmitted by means which have heretofore been described to mold 72 which moves upwardly to casting position as illustrated in Fig. 12. Bar 82 and ejector rods 84 are simultaneously moved downwardly due to the pin and slot connection 79, 78. Continued movement of lever 25 causes the valve 58 to be moved in the direction of its length to bring the openings 59 therein into register with the openings in the apertured member 86 and the openings between the lugs or shoulders 83 of member 81, whereupon molten metal flows into the mold and into the indented characters formed in the lower surfaces of the type bars. Bar 82 and shoulder 72' give the slug the form that is illustrated in Fig. 13, which is the form required in present multigraph machines.

When rod 25 is released and weight 36 is permitted to return the parts to normal position, valve 58 is first moved to shut off the flow of molten metal. As mold 72 moves downwardly the pin and slot connection 79, 78 force beam 80 upwardly carrying bar 82 out of engagement with slug 73. Continued movement results in the ejector rods 84 engaging the slug on its lower side between the upper and lower shoulders and positively forcing the slug into a pocket formed by the enlarged portion 75' of mold casing 75. The cast slug then moves of its own weight down the inclined surface of casing 75 on to the tray 64.

By the use of my improved machine, expert operators can obtain a speed equal to ordinary speech. Operation of the letter keys is noiseless.

While only one form of the inventive idea has been described and illustrated in the accompanying drawings it is to be expressly understood that the drawings are for purposes of illustration only and are not designed as a definition of the limits of the invention, reference being had for this purpose to the appended claims.

What I claim is:—

1. A device of the class described com-

prising a frame, a plurality of rectilinearly movable type bars mounted thereon, said bars being provided with printing and matrix characters, means for selectively limiting movement of said bars in one direction, a platen adapted to co-act with said printing characters, means adapted to co-act with said matrix characters for forming a linotype slug, and common actuating means for said platen and last-named means.

2. In combination with a plurality of movable type bars having two sets of characters formed therein, a platen mechanism movable into engagement with one of said sets of characters, casting mechanism adapted to co-act with the other of said sets of characters, common actuating means for said platen, type bars, and casting mechanism, and means for setting stops simultaneously for a plurality of said bars.

3. In combination with a plurality of movable type bars having printing and matrix characters formed therein, simultaneously operative elements for selectively limiting movement of said bars for bringing the characters on said bars into alignment, means for printing said aligned printing characters, means for forming a casting of said aligned matrix characters, and common actuating means for said printing and casting means and for moving said type bars into engagement with said first named means.

4. In combination, a frame, a plurality of rectilinearly movable type bars mounted thereon, said bars having raised characters on the upper surfaces thereof and indented characters in the lower surfaces of the same, means for limiting the movement of said bars, casting means, platen means, and means for moving said platen into engagement with said raised characters and actuating said casting means.

5. In combination, printing mechanism including a plurality of rectilinearly movable bars provided with type and matrix characters and platen mechanism, casting mechanism adapted to cooperate with said matrix characters including a receptacle for molten metal and a control valve therefor, a mold, and common actuating means for said bars, said mold and platen mechanism.

6. In combination, a frame, printing mechanism including a plurality of slidably type bars having type and matrix characters formed thereon and mounted on said frame, casting mechanism carried by said frame, means common to said type bars and said printing and casting mechanism for actuating the same, and means for setting stops for a plurality of said bars simultaneously.

7. In combination, a frame, printing mechanism mounted on said frame, casting mechanism carried by said frame, means including a lever, a drum, and flexible means

connecting said lever and drum, common to said printing and casting mechanism for simultaneously actuating the printing and casting mechanisms and a plurality of letter-keys movable independently of said last named means.

8. A device of the class described comprising, in combination with printing mechanism, a reservoir for metal to be cast, means for heating said metal, a mold casing having a curved groove therein, a movable mold in said casing, a valve for controlling the flow of metal into the mold, means for moving said mold and actuating said valve, and means operatively engaging said groove for positively ejecting a cast slug from said mold.

9. In combination, printing mechanism a plurality of rectilinearly movable type bars provided with raised and indented characters, and casting mechanism mounted below said bars including a mold for forming multigraph slugs, and means for moving said mold to casting position.

10. In a device for forming multigraph slugs the combination of a frame, a plurality of members having indented letter characters formed therein, a reservoir containing metal for forming said slugs, means for heating said metal, a control valve for said reservoir, a mold, and means for simultaneously moving said mold and members toward casting position.

11. A casting device comprising a reservoir for metal to be cast, means for heating said metal, a plurality of rectilinearly movable bars having indented letter characters therein, a mold for multigraph slugs, means for controlling the flow of metal from said reservoir to said mold, and actuating mechanism for said controlling means.

12. A casting device comprising a reservoir for type metal, means for heating said type metal, a mold, a plurality of rectilinearly movable bars carrying type and matrix characters positioned adjacent said mold and adapted to cooperate therewith, means for controlling the flow of molten metal from said reservoir, and actuating mechanism for said last-named means.

13. A device of the class described comprising a frame, a plurality of slidably mounted bars on said frame, said bars being provided with type and matrix characters, a platen mechanism adapted to co-operate with said bars, means cooperating with said bars for forming a linotype slug, common actuating means for moving the bars, the platen, and said last named means, and means operable independently of said common actuating means for selectively limiting the movement of said type bars in one direction.

14. In combination with a plurality of movable type bars having raised and in-

dented characters, a platen mechanism adapted to cooperate with said raised characters, casting mechanism adapted to cooperate with said indented characters, and 5 common means for simultaneously moving all of said bars and for bringing the platen and casting mechanism into cooperative relation with said raised and indented characters respectively.

10 15. In combination with a plurality of movable type bars having raised and indented characters, means including a manually operable member for moving said bars, means for selectively limiting movement of 15 said bars for bringing type characters on the same into alinement, means for printing the raised alined characters, and means for forming a casting of the indented alined characters, said printing and casting means

being actuated by movement of said manually operable member.

16. In combination with a plurality of movable type bars provided with raised and indented characters, platen mechanism adapted to cooperate with said raised characters, casting mechanism adapted to cooperate with said indented characters, common means for moving all of said bars and for bringing the platen and casting mechanisms into cooperative relation therewith, and means for disconnecting said casting mechanism whereby the type bars and platen mechanism may be independently actuated.

In testimony whereof I have signed this 35 specification.

FRED A. DOLPH.
